UNITED STATES PATENT OFFICE.

SAMUEL DUNCAN BLACK AND ALONZO G. DECKER, OF TOWSON, MARYLAND,
ASSIGNORS, BY MESNE ASSIGNMENTS, TO SECOND NATIONAL BANK OF
BALTIMORE, TRUSTEE, OF BALTIMORE, MARYLAND.

DESIGN FOR A COMBINATION MOTOR AND AIR-PUMP CASING.

58,177.

Specification for Design.

Patented June 21, 1921.

Application filed June 14, 1920. Serial No. 389,028. Term of patent 14 years.

To all whom it may concern:

Be it known that we, SAMUEL DUNCAN BLACK and ALONZO G. DECKER, citizens of the United States of America, and residents of Towson, county of Baltimore, State of Maryland, have invented a certain new, original, and ornamental Design for a Combination Motor and Air-Pump Casing, of which the following is a specification.

In the accompanying drawing we have illustrated a portable system for dispensing air, constructed in accordance with our invention.

The figure is a perspective view of the same.

The air-dispensing system as shown consists of a suitable casing, inclosing pumping apparatus or the like, an elongated, upright, cylindrical tank, a truck on which the system is mounted, the same being closely assembled in compact relation, with the tank

in upright position as aforementioned, and substantially equally distributed on each side of the axle of the rear wheels of the truck.

The truck includes a rearwardly extending frame supporting the tank, and this frame serves as a means for connecting to the truck a yoke, or grip, with a cross-bar for manual control in handling and propelling.

Having thus described and illustrated our invention, we claim:

The ornamental design for a combination motor and air pump casing, substantially as shown and described.

Signed by us at Towson, Maryland, this 6th day of May, 1920.

SAMUEL DUNCAN BLACK.
ALONZO G. DECKER.
